UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 13,373, dated October 31, 1882.

Application filed August 11, 1882. Term of patent 3½ years.

To all whom it may concern:

Be it known that I, OTTO HEINIGKE, of New Utrecht, in the State of New York, have invented a new and original Design for Carpets, 5 of which the following is a specification.

This invention relates to a new and original design for carpets and similar fabrics; and it consists in the novel grouping and configuration of figures hereinafter more fully described.

10 The accompanying photograph illustrates a face view of a carpet having my new design. The design for the body of the carpet consists of a plain ground, A, closely filled with long curving leaf-sprays having long narrow-15 lobed leaves, and with the spaces evenly filled in with unconnected leaves of similar shape. At regular intervals over the face of the design occurs the figure B, resembling a many-rayed star figure, and having a center with three 20 small figures in it.

The design for the border, also shown in the photograph, consists of several broad and narrow bands, as follows:

C is a narrow inner band, ornamented with 25 a series of small and scalloped figures.

D is a broader band, consisting of larger and smaller figures resembling the figures B of the body design, loosely scattered over a blank field, which field also contains a broad and low flower-30 like figure and various scattered small figures.

E is a broad band, having a series of small scalloped figures on its inner and outer edges, and including various narrow bands in between these, each differently ornamented, the 35 central band having a double series of semicircular figures. A large many-lobed leaf al-

ternates with a figure resembling B of the body design, and overlies the various narrow bands constituting the broad band E.

F is the broad outer band and completes the 40 border design. Its inner portion is ornamented with a series of overlapping semicircular figures, and its outer portion with a series of symmetrical figures projecting outward into a blank field.

45 I claim—

1. The design for carpets, consisting of the ground A, substantially as shown.
2. The design for carpets, consisting of the figure B, substantially as shown.
3. The design for carpets, consisting of the ground A and figure B, substantially as shown.
4. The design for carpets, consisting of the band C, substantially as shown.
5. The design for carpets, consisting of the 55 band D, substantially as shown.
6. The design for carpets, consisting of the bands C and D, substantially as shown.
7. The design for carpets, consisting of the band E, substantially as shown.
8. The design for carpets, consisting of the bands C, D, and E, substantially as shown.
9. The design for carpets, consisting of the band F, substantially as shown.
10. The design for carpets, consisting of the 65 bands E and F, substantially as shown.
11. The design for carpets, consisting of the bands C, D, E, and F, substantially as shown.

OTTO HEINIGKE.
